(57) **CLAIM**

The ornamental design for an LED package, as shown and described herein.

DESCRIPTION

FIG. 1 is a top perspective view of an LED package according to one embodiment of the present invention.

FIG. 2 is a front elevation view of one side of the LED package shown in FIG. 1.

FIG. 3 is a back elevation view of the LED package as shown in FIG. 1.

FIG. 4 is an elevation view of one side of the LED package shown in FIG. 1, with the other side being substantially the same.

FIG. 5 is a top view of the LED package shown in FIG. 1.

FIG. 6 is a bottom view of the LED package shown in FIG. 1.

FIG. 7 is a top perspective view of an LED package according to another embodiment of the present invention.

FIG. 8 is a front elevation view of one side of the LED package shown in FIG. 7.

FIG. 9 is a back elevation view of the LED package as shown in FIG. 7.

FIG. 10 is an elevation view of one side of the LED package shown in FIG. 7, with the other side being substantially the same.

FIG. 11 is a top view of the LED package shown in FIG. 7.

FIG. 12 is a bottom view of the LED package shown in FIG. 7.

FIG. 13 is a top perspective view of an LED package according to another embodiment of the present invention.

FIG. 14 is a front elevation view of one side of the LED package shown in FIG. 13.

FIG. 15 is a back elevation view of the LED package as shown in FIG. 13.

FIG. 16 is an elevation view of one side of the LED package shown in FIG. 13, with the other side being substantially the same.

FIG. 17 is a top view of the LED package shown in FIG. 13; and,

FIG. 18 is a bottom view of the LED package shown in FIG. 13.

The regular broken lines shown in the above figures depict environmental subject matter only and form no part of the claimed design in those embodiments.
